(57) **CLAIM**

We claim the ornamental design for a display screen or
portion thereof with a graphical user interface, as shown and
described.

DESCRIPTION

The single FIGURE is a front view of a display screen or
portion thereof with a graphical user interface showing our
new design.

The grayscale shading within the solid line rectangular
shapes indicates contrasts in appearance. The outermost
broken line showing the display screen or portion thereof
and all other broken lines showing portions of the graphical
user interface are included for the purpose of illustrating
portions of the article and form no part of the claimed
design.
